UNITED STATES PATENT OFFICE.

WILLIAM KRAFVE, OF FALL RIVER, MASSACHUSETTS.

SPRING.

1,354,978.

Specification of Letters Patent.

Patented Oct. 5, 1920.

Application filed December 12, 1919. Serial No. 344,387.

To all whom it may concern:

Be it known that I, WILLIAM KRAFVE, a citizen of the United States, residing at Fall River, in the county of Bristol and State of Massachusetts, have invented new and useful Improvements in Springs, of which the following is a specification.

This invention relates to certain new and useful improvements in springs, and relates more particularly to springs used in connection with motor trucks.

Ordinarily motor truck springs are provided with connectors formed by simply bending the top leaf over to form a loop, but this structure is objectionable since in going over rough roads the unsupported loop is subjected to constant strain and an opening tendency, with the result that the loop is crystallized and soon breaks.

The primary aim of the present invention is to provide an improved form of spring in which a permanent rigid loop is formed at each end of the spring, and in which the loop is reinforced so as to give it additional strength.

The invention further aims to provide a simple and economical structure and one of great strength and longevity.

In the drawings:

Figure 1 is a top plan view of the invention.

Fig. 2 is a side elevation, and

Fig. 3 is an enlarged section on line 3—3 of Fig. 1.

In proceeding in accordance with the present invention the usual form of leaf spring structure 1 is employed, the top leaf 2 of which is looped at its ends at 3 and formed with a flat part 4 which seats on the upper face of the top leaf 2. The part 4 has its free end 5 turned upwardly to form a stop for a clip 6, thereby to prevent movement of the clip longitudinally of the spring. Longitudinal movement of the clip in the reverse direction is prevented by the vertical part 7 of the loop 3. The clip is secured in position by means of the bolts 8 which latter are engaged on opposite sides of the

spring structure 1 and on opposite sides of the flat part 4 so as to prevent the loop terminal from shifting laterally of the spring structure 1.

For the purpose of reinforcing the loop and imparting additional strength thereto the second leaf 9 is formed with a loop 10 which is conformably engaged with and about the loop 3 and extends over the top of the latter and beyond the suspension point thereof.

From the foregoing it will be apparent that it is impossible for the loop to open or otherwise move, due to its positive anchorage effected by the clip, the flat part 4 and the stop parts 5 and 7. Further the loop itself is reinforced by the curved end 10 of the under leaf 9, so that a strong durable and efficient structure results.

It will be understood that the structure at each end of the spring is identical as described in the foregoing.

Having thus described my invention, what I claim as new and desire to secure by Letters Patent is:—

1. In a spring, a leaf structure having the ends of the top leaf looped over and provided with flat parts seating on the top face of the top leaf, the free terminals of the flat parts being bent upwardly to form stops, clips seating on the top faces of the flat parts and disposed between the stops and the adjacent sides of the loops, and bolts engaged with the opposite sides of the flat part for securing the clips in position, the ends of the second leaf being bent over and superimposed upon the loops of the first leaf.

2. In a spring, a leaf structure having the ends of the top leaf looped over and provided with flat parts seating on the top face of the top leaf, the free terminals of the flat parts being bent upwardly to form stops, and means between the stops and the adjacent parts of the loops for securing the flat parts downwardly onto the top leaf.

3. In a spring, a leaf structure having the ends of the top leaf looped over and pro-

vided with flat parts seating on the top face of the top leaf, and means for securing said flat parts in position in engagement with the top face of the top leaf, the leaf beneath 5 the top leaf having its ends bent around and seated upon said loops.

4. In a spring, a leaf structure having the ends of the top leaf formed with loops, and means for securing said loops rigidly 10 in position, the ends of the underlying leaf

being bent to engage over and around and seating upon said loops.

In testimony whereof I have signed my name to this specification in the presence of two subscribing witnesses.

WILLIAM KRAFVE.
